ATTORNEYS

UNITED STATES PATENT OFFICE.

GEORGE WILBUR BROWN, OF MILLWOOD, WASHINGTON, ASSIGNOR TO INLAND EMPIRE PAPER CO., OF MILLWOOD, WASHINGTON, A CORPORATION OF WASHINGTON.

SAVE-ALL.

Application filed April 6, 1921. Serial No. 458,927.

To all whom it may concern:

Be it known that I, GEORGE W. BROWN, a citizen of the United States, and a resident of Millwood, in the county of Spokane and State of Washington, have invented a new and Improved Save-All, of which the following is a full, clear, and exact description.

The invention relates to paper making and fiber liberation, and its object is to provide a new and improved save-all arranged to separate effectively the pulp fibers from the waste water discharged from apparatus handling of the raw stock or from the paper-making machine.

Another object is to permit of operating the save-all without requiring any power except that for running a conveyor to carry off the recovered stock.

Another object is to permit of conveniently adjusting the save-all for use with different stock.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in both views.

Figure 1 is a perspective view of the improved save-all; and

Figure 2 is a sectional side elevation of the same.

The base of the separating machine is in the form of a basin 10 for receiving the water after it is separated from the stock, and this basin 10 is provided with an outlet pipe 11 for carrying off the water. At the rear of the basin 10 are erected posts 12 which support a trough or a flume 13 closed at one end and connected at its other end with the apparatus handling the raw stock or with the paper-making machine to allow the waste water containing the pulp fibers to flow through the trough or flume 13 to the discharge end thereof. The front of the trough or flume 13 is provided with a plurality of gates 14 for discharging the waste water onto the upper end of a screen 15 inclined downwardly and forwardly. The upper end of the screen 15 is hinged or piv-

oted at 16 to the bottom of the trough 13 at the front edge thereof, and the lower end of the said screen 15 is provided with adjusting means 17, such as a turnbuckle, connecting the screen with the basin 10 to allow of varying the incline or angle of the screen 15 according to the nature of the pulp under treatment at the time.

The upper portion 20 of the screen 15 is preferably of a finer mesh than the lower portion 21; for instance, the upper portion 20 is preferably of 100-mesh while the lower portion 21 is of 60 to 70-mesh. The fine upper mesh portion 20 serves to start the gathering of the stock on the top of the screen, and once the stock has gathered, the mass tends to act as a filter for the white water following behind so that all except the most minute fibrous particles are saved and consolidated with the mass of stock, which by its own weight tends to roll down the inclined screen to the lower end thereof. A jet or shower pipe 22 is preferably mounted to turn in bearings 23 attached to the posts 12 immediately in the rear of the upper portion 20 of the screen 15 to deliver jets of water against the said upper screen portion to keep the meshes of the screen open, free of slime or other extraneous matter. A rocker arm 24 is preferably attached to the pipe 22 and connected with other machinery for rocking the pipe 22 to direct the jets to a large area of the screen 15.

The lower end of the inclined screen 15 discharges into the conveyor box 25 of a conveyor of any approved construction but one that is preferably provided with wooden flights 26 attached to a chain 27 passing around wheels 28 mounted in the box 25. One of the wheels is driven by means not illustrated in the drawings. The wooden flights 26 on the lower run of the chain 27 are in close proximity to the bottom of the box 25 to readily move the separated stock forward in the box 25 to a suitable place of discharge.

From the foregoing it will be seen that by the arrangement described the stock and water are effectively separated and the recovered stock is returned to the raw stock end of the mill for manufacture into paper.

The save-all shown and described is very simple and durable in construction and not liable to get out of order easily, and the save-

all requires no power for its operation except running the conveyor to carry off the recovered stock.

Having thus described my invention, I claim as new and desire to secure by Letters Patent:

1. A save-all comprising a delivery means for the waste water, an adjustable screen in front of the delivery means and inclined downwardly and forwardly therefrom to allow the water to separate from the stock and pass through the screen and to allow the separated stock to travel down the screen, and an endless conveyor into which discharges the lower end of the said screen for carrying off the stock separated from the waste water.

2. A save-all comprising a delivery trough for the waste water, an adjustable screen in front of the delivery trough and inclined downwardly and forwardly therefrom to allow the water to separate from the stock and pass through the screen and to allow the separated stock to travel down the screen, a conveyor into which discharges the lower end of the said screen for carrying off the stock separated from the waste water, and a basin from which the trough is supported and arranged under the said screen for collecting the water passing through the screen.

3. A save-all comprising a delivery means for the waste water, a screen in front of the delivery means and inclined downwardly and forwardly therefrom to allow the water to separate from the stock and pass through the screen and to allow the separated stock to travel down the screen, a conveyor into which discharges the lower end of the said screen for carrying off the stock separated from the waste water, and a jet pipe connected with a water supply and extending under the upper portion of the screen to deliver jets of water against the under side of the screen.

4. A save-all comprising a delivery means for the waste water, a screen in front of the delivery means and inclined downwardly and forwardly therefrom to allow the water to separate from the stock and pass through the screen and to allow the separated stock to travel down the screen, the upper portion of the said screen being of a finer mesh

than the lower portion thereof, and a conveyor into which discharges the lower end of the said screen for carrying off the stock separated from the waste water.

5. A save-all comprising a delivery trough closed at one end and provided at the front with gates, an inclined screen having its upper end at the said gates to receive the waste water, the upper portion of the screen being of finer mesh than the lower screen portion, the upper end of the screen being pivoted, adjusting means on the lower end of the screen to adjust the screen to a desired angle, and means for receiving and carrying off the pulp separated from the water and traveling down the screen by its own gravity.

6. A save-all comprising a delivery trough closed at one end and provided at the front with gates, an inclined screen having its upper end at the said gates to receive the waste water, the upper portion of the screen being of finer mesh than the lower screen portion, the upper end of the screen being pivoted, adjusting means on the lower end of the screen to adjust the screen to a desired angle, means for receiving and carrying off the pulp separated from the water and traveling down the screen by its own gravity, and a water jet pipe connected with a water supply and extending under the upper portion of the screen to deliver jets of water against the said screen.

7. A save-all, comprising a delivery trough closed at one end and provided at the front with gates, an inclined screen having its upper end at the said gates to receive the waste water, the upper portion of the screen being of finer mesh than the lower screen portion, the upper end of the screen being pivoted, adjusting means on the lower end of the screen to adjust the screen to a desired angle, means for receiving and carrying off the pulp separated from the water and traveling down the screen by its own gravity, a water jet pipe connected with a water supply and extending under the upper portion of the screen to deliver jets of water against the said screen, and a catch basin under the screen for collecting the water passing through the screen.

GEORGE WILBUR BROWN.
